UNITED STATES PATENT OFFICE

2,215,730

LADY'S HANDBAG

Albert Wallman, Bissett, Manitoba, Canada

Application March 22, 1939, Serial No. 263,544

2 Claims. (Cl. 240—6.45)

My invention relates to ladies' handbags, and has among its objects and advantages the provision of an illuminated mirror incorporated in the handbag structure.

5 In the accompanying drawing:

Figure 1 is a perspective view of a handbag illustrating my invention applied thereto;

Figure 2 is a fragmentary view of the mirror, its mounting and the electric lamp;

10 Figure 3 is a sectional view taken along the line 3—3 of Figure 2;

Figure 4 is a view taken along the line 4—4 of Figure 1; and

15 Figure 5 is a perspective view of a portion of the mirror frame.

In the embodiment selected to illustrate my invention, the handbag 10 is of conventional construction and includes the usual side walls 12, jaws 14 and latch 16. To one of the walls 12 inside the bag 10 I mount a battery receptacle 18 which includes a bottom 20, a side wall 22 and end walls 24 and 26. Bottom 20 and the end walls 26 are flanged at 28 and secured to the associated wall 12 by rivets 30.

20 On the outer face of the wall 12 I mount a mirror 32 about the margin of which I position a frame 34. Frame 34 includes side reaches 36 and 38 and end reaches 40 and 42.

Fig. 5 illustrates the reach 38 in cross section, 30 which reach includes a flange 44 which partly overlaps the exterior face of the mirror 32 and another flange 46 which extends across the associated edge of the mirror. All the frame runs are identical in construction. Each frame run 35 includes a flange 48 which lies against the outer face of the wall 12 and is secured thereto by the rivets 30, which secure the battery receptacle 22, see Fig. 3.

Between the mirror 32 and the associated wall 40 12, I mount a plate 52 which is slit to provide ears 54 pressed through the wall 12 and bent back upon the wall, as at 56. Plate 52 is provided with an extension 58 bent to provide a reflector 60 substantially semi-circular in cross section. Reflector 60 extends outwardly from the mirror 32 and is arranged to reflect light thereon emanating from an electric lamp 62 having its bulb 64 threaded into the socket 66 riveted at 68 to the mirror 60. The central terminal 70 of the electric lamp 62 is normally in spaced relation with the switch arm 72 comprising an extension of the frame run 38, see Fig. 5.

Reflector 60 is slotted at 74 for receiving the body 76 of a switch cam 78 located inside the reflector 60. A knob 80 is secured to the body

76 for shifting the switch cam 78 to off and on positions.

Fig. 2 illustrates the switch cam 78 as having its end located between the face of the reflector 60 and the switch arm 72 so that the latter will be urged into connecting relation with the central terminal 70 when the knob 80 is pushed in the direction of the arrow 82.

A battery 84 is located inside the battery receptacle 22, and the wall 26 carries an elevation 86 arranged in contact with the terminal at one end of the battery. The terminal 88 of the battery is arranged in contact with the spring arm 90 extending through an opening 92 in the wall 12 and constituting an extension of the plate 52. 15 Thus it is seen that when the switch arm 72 is pulled into contact with the central terminal 70 the circuit to the lamp will be closed as follows: from the battery 84 to the spring contact 90, reflector 60, lamp 62, spring arm 72 through 20 the medium of the contact 70, frame 34 to the battery receptacle 22 through the medium of the rivets 30 and to the battery 84 through the medium of the contact 86. Insulation 94 is located against the inner face of the end wall 24 so as 25 to shield the spring contact 90.

Closing of the switch closes the circuit to the lamp 62 which illuminates the reflector 60. Reflector 60 is so arranged as to reflect the light rays upon the mirror 32 for illuminating the same. Battery receptacle 22 is of small proportions and is located inside the handbag, while the mirror 32 lies flat against the one wall 12 and is effectively secured thereto through the medium of the frame 34. 35

I provide means for mounting the battery inside the handbag with the mirror located externally thereof. The construction is such as to eliminate the necessity for cutting openings in the wall of the handbag other than mere perforations 40 for accommodating the rivets 30. The reflector affords protection for the electric lamp in addition to effectively reflecting the light rays upon the mirror for illuminating purposes. Frame 34 in combination with the flanged battery receptacle is clamped to the side wall 12 and effectively secures the parts in connected relation. 45

I claim:

1. In a handbag of the type described, a battery support inside the bag and having a contact for engaging one contact of the battery, a mirror located outside the bag, a frame secured to the bag outside the latter for supporting the mirror, said frame being electrically connected with the contact of said support, a plate secured 55

to the handbag underneath the mirror and having a contact arm extending into the bag for engagement with the other terminal of the battery, said plate being provided with a reflector, an 5 electric lamp supported by said reflector and having one of its terminals electrically connected therewith, a spring arm carried by said frame and arranged for electrically engaging the other terminal of said electric lamp, and a switch carried 10 by the reflector for moving said spring contact arm into engagement with its respective lamp terminal for closing the circuit through the lamp.

2. In a handbag of the type described, a battery receptacle secured to one wall of the bag inside the latter, said battery receptacle being provided with a contact for engaging one contact of the battery, a mirror located outside the bag adjacent 15 said one wall thereof, a frame for secur-

ing the mirror to said one wall of the bag and electrically connected with said receptacle, a plate secured to said one wall of the bag underneath the mirror and having a contact arm extending through said one wall of the bag for engagement with the second contact of the battery, said plate having a curved reflector, an electric lamp supported by said reflector adjacent its concaved face, said electric lamp having one terminal electrically connected with the reflector, said 10 frame being provided with a curved spring arm lying adjacent the concave face of said reflector and arranged to be moved into electrical engagement with the other terminal of said electric lamp, and a switch slidably connected with said 15 reflector and arranged to move said curved spring arm into electrical engagement with the second terminal of the electric lamp.

ALBERT WALLMAN.
